INVENTOR.

UNITED STATES PATENT OFFICE.

WILHELM WEIGANG, OF BAUTZEN, GERMANY, ASSIGNOR TO CARL O. VON KÖKERITZ, OF MOUNT VERNON, NEW YORK.

DESIGN FOR A CIGAR-BAND.

No. 39,928.

Specification for Design.

Patented April 20, 1909.

Application filed December 15, 1908. Serial No. 467,723. Term of patent 3½ years.

To all whom it may concern:

Be it known that I, WILHELM WEIGANG, a subject of the Emperor of Germany, residing at 6 Wallstrasse, Bautzen, Germany, have invented a new, original, and ornamental Design for Cigar-Bands, of which the following is a specification, reference being had to the accompanying drawing, forming part thereof.

The figure is a plan view of a cigar band, showing my new design.

I claim:

The ornamental design for a cigar band, as shown.

WIH. WEIGANG.
